UNITED STATES PATENT OFFICE.

WALTER KIESER, OF BERLIN, GERMANY, ASSIGNOR TO GENERAL ELECTRIC COMPANY,
A CORPORATION OF NEW YORK.

STEAM-TURBINE NOZZLE.

1,112,295.

Specification of Letters Patent. Patented Sept. 29, 1914.

Application filed October 1, 1912. Serial No. 723,310.

To all whom it may concern:

Be it known that I, WALTER KIESER, a citizen of Switzerland, residing at Berlin, Germany, have invented certain new and useful 5 Improvements in Steam-Turbine Nozzles, of which the following is a specification.

This invention relates to elastic fluid turbines and its object is to provide an expanding nozzle which will avoid the losses due to 10 an imperfect or improper expansion of the steam.

The invention consists in a nozzle whose partition walls terminate at or near to the smallest point in the nozzle, while the boundary walls extend to the exit end of the nozzle. This permits the steam to expand between said boundary walls in accordance 15 with the existing counter-pressure. With decreasing counter-pressure, the stream of steam will be curved backwardly more and more after leaving the partition walls, whereby the greater ratio of expansion is given which is necessary in this case. Under some circumstances, ordinary directing devices may be used instead of nozzles, said devices having side walls parallel to the exit ends, which simplifies manufacture. In the case of cast nozzles, a slight enlargement of 20 the cross-section of the steam passage beyond its smallest point can hardly be avoided for structural reasons, but this need not be determined with exactness, and so in this case also a considerably cheaper process of manufacture is obtained. The two boundary 25 walls of the nozzle are preferably kept parallel from the termination of the partition walls, but this is not essential.

In the accompanying drawing, Figure 1 is a section of a portion of a multi-jet nozzle 40 having sheet metal partition walls; Fig. 2 is a section on the line 2—2, Fig. 1; Figs. 3 and 4 show similar views of a cast metal construction.

In Figs. 1 and 2, the partition walls 1 are preferably constructed of sheet metal; but whatever the material may be, they terminate at 2, which is the narrowest point in the passage for the steam through the nozzle, and some distance back from the exit end 45 thereof. The boundary walls 3, 4 are carried beyond the ends of the partitions to such an extent that the desired expansion of the

steam is obtained in the nozzle, even at the lowest counter-pressure. The depth of the boundary walls beyond the ends of the partitions will vary, depending upon whether or not a supplementary expansion is permitted in the gap between the nozzles and the bucket wheel. The boundary walls are 55 preferably parallel.

In Figs. 3 and 4, the partitions 5 and boundary walls 6, 7 are of cast metal, being 60 preferably integral. The partitions run only a short distance beyond the narrowest point 8, and the boundary walls may be either parallel or slightly divergent from this point, or even converge slightly, if found necessary. If divergent, then the enlargement of the nozzle thereby produced should be only so great that at the smallest desired expansion 65 the space between the walls 6, 7 beyond the ends of the partition is nevertheless filled with steam.

In accordance with the provisions of the patent statutes, I have described the principle of operation of my invention, together with the apparatus which I now consider to represent the best embodiment thereof; but I desire to have it understood that the apparatus shown is only illustrative, and 70 that the invention can be carried out by other means.

What I claim as new, and desire to secure by Letters Patent of the United States, is:—

1. A steam turbine nozzle having its boundary walls extending to its outer end, and its partitions terminating at a distance from the exit end of said nozzle sufficiently far to permit the steam to expand to substantially the true counterpressure before emerging 85 from between said boundary walls.

2. A steam turbine nozzle for varying counterpressure, having its boundary walls extending to its outer end, and its partitions terminating adjacent to the narrowest point 90 in said nozzle, said point lying sufficiently far from the outer end to permit the steam to expand within the nozzle to substantially the true counterpressure.

3. A steam turbine nozzle for varying 100 counterpressure having boundary walls extending to its exit end and partition walls terminating sufficiently far back from its exit end to permit free expansion of the

steam in the nozzle to substantially the true counterpressure under all conditions of operation, the distance apart of the adjacent surfaces of adjacent partitions being uniform for a substantial distance back from their ends.

In witness whereof, I have hereunto set my hand this 16th day of September, 1912.

WALTER KIESER.
